UNITED STATES PATENT OFFICE.

AUGUSTUS H. SEXTON, OF INDIANAPOLIS, INDIANA, ASSIGNOR TO DAVID L. SHORT,
OF PHILADELPHIA, PENNSYLVANIA.

HAIR CURLING AND WAVING DEVICE.

Application filed June 22, 1925. Serial No. 38,850.

This invention relates to a device that is adapted to be used instead of a covered bendable wire or the like on which human hair may be wrapped to cause curling of the hair, the wires hitherto used being liable to break after being repeatedly bent or heated, so as to become useless and therefore resulting in loss, this invention relating especially to a curling device that is adapted 10 to be repeatedly used as long as it may be needed.

An object of the invention is to provide an improved hair curler of the above-mentioned character which shall be of such construction 15 as to be capable of securely holding a strand of hair until the curling of the hair is effected, and which shall not be complicated and costly.

Another object is to provide a hair curler 20 which shall be capable of conveniently holding hair to be curled and also capable of withstanding heat when it may be desired to insert the hair into a hollow heater for hastening the curling process.

25 A further object is to provide a hair curler that shall be adapted to clamp a strand of hair when wound thereon and which may be readily removed from the wound hair without disarranging the windings of the hair, 30 an aim being to obtain quick and artistic results when curling and waving human hair.

With the above-mentioned and other objects in view, the invention consists in novel 35 clamping apparatus constructed to permit a strand of hair to be wound thereon and to permit quick removal of the apparatus from the hair following the curling process, the invention consisting further in the parts and 40 combinations and arrangements of parts as hereinafter particularly described and further set forth in the appended claim.

Referring to the drawings,—Figure 1 is a side view of the hair curler and waver on 45 which a strand of hair is wound to accomplish curling and waving of the hair; Fig. 2 is a side view of the curling and waving device; Fig. 3 is a front view of the device on a reduced scale; Fig. 4 is a side view of 50 the device on a reduced scale illustrating the manner of operation thereof; Fig. 5 is a fragmentary section approximately on the line V—V in Fig. 2, on a greatly enlarged scale; Fig. 6 is a transverse section on the line VI—VI in Fig. 2 on an enlarged scale;

and Fig. 7 is a transverse section on the line VII—VII in Fig. 2.

Similar reference characters in the various figures of the drawings indicate corresponding elements or features of construction 60 herein referred to in detail.

In the drawings the numeral 1 indicates a fragment of a head of hair from which a strand of hair 2 is divided out to be curled.

An embodiment of the invention comprises 65 a straight curler rod 3, which preferably is hollow and may be composed of tubing, on which to wrap or wind the strand of hair to carry out the curling process. A clamp bar 4 is provided which may be composed of thin 70 sheet metal and is curved so as to be semi-circular in cross section to partially receive the rod 3, the clamp bar being of such length as may be desired, such as shown in Fig. 3; or it may be nearly as long as the rod so as 75 to have a manipulation extension portion 4'. The clamp bar has hinge ears 5 and 6 on its edges adjacent to one end of the bar, the ears being arranged to loosely embrace the rod 3 adjacent to one end thereof. 80

Two retaining rods 7 and 8 are provided which preferably are composed of spring-wire, the major portions of the rods being normally straight and having obtuse-angled hinging portions 9 and 10 respectively that 85 are arranged adjacent to the hinge ears and are provided with hinge pins 11 and 12 respectively that are inserted oppositely through suitable holes in the ears and the rod 3 adjacent to one end of the rod. The 90 opposite ends of the rods 7 and 8 have obtuse-angled latch portions 13 and 14 adapted to extend beyond the opposite end of the rod 3 and are integrally connected with an axle 15 on which is a spherical roller 16 to be 95 drawn over the adjacent end of the rod 3 and become seated in the open end of the rod if tubular, the rod having a socket 17 in its end to receive the roller in case the rod is not tubular, the roller having a bore loosely receiving the axle. The relatively angular portions permit effective elongation of the retaining rods to permit the roller to be sprung over the edge of the rod 3 and into or out of the opening in its end. 100

In practical use the retaining rods are swung away from the rod 3 and the clamp bar 4 is swung also sufficiently to receive the end portion 18 of the strand of hair between the bar and the rod 3 adjacent to the hinge 110

ears, after which the bar 4 is swung back, as may be seen in Fig. 4 and also farther until the bar 4 comes against the rod 3, after which the device is turned so as to cause the 5 strand to be wrapped in close coils 19 about the rod 3 and the clamp bar 4, to produce curling of the hair, the device being further rotated and the strand of hair guided so as to be spirally wound about the device to 10 form open or separated coils 20 which will result in waving of the hair on completion of the process. Having wrapped the strand of hair on the rod 3, the retaining rods are swung over onto the coils of hair and the 15 roller 16 is pressed into latching position, and in case the hair coils are unusually thin the roller may be forced over the farther edge portion of the end of the rod 3 to more tightly clamp the coils in place, the relative 20 position of the roller being indicated by dotted lines in Fig. 2. In some cases the hair may be retained by the apparatus during the night time to accomplish the purpose but may be placed in a hollow or tubular 25 electrical heater and thereby obtain the desired results within a very short time. Usually the curling apparatus is quickly removed from the hair coils by first unlatching the retaining rods and swinging 30 them over approximately as shown in Fig.

4, pushing the clamp bar 4 slightly away from the rod 3 and then pulling the rod and the bar out of the coils while holding the coils by hand as the device is drawn from them. The final result is wavy hair in 35 proximity to the head and the curling of the remaining end portions of the hairs.

What is claimed as new is:

A hair curling and waving device comprising a hollow curler rod, a clamp bar 40 to co-operate with the rod having two ears on opposite edges adjacent to one end of the bar, the ears being arranged on opposite sides of the curler rod adjacent to one end of the rod, two retaining rods having each a relatively obtuse-angled hinge portion on one end and a relatively obtuse-angled latch portion on the opposite end thereof, the hinge portions being provided with hinge pins that are connected to said ears respectively and also to the adjacent portion of the curler rod, the latch portions of the retaining rods having an axle integral therewith, and a spherical roller arranged on the axle to be carried thereby partially into the 45 opposite end of the hollow curler rod.

In testimony whereof, I affix my signature on the 18th day of June 1925.

AUGUSTUS H. SEXTON.
